US0D1112605S

(12) **United States Design Patent** (10) **Patent No.:** **US D1,112,605 S**
(45) **Date of Patent:** **** Feb. 10, 2026**

(54) **PORTABLE REVERSE OSMOSIS SYSTEM**

(71) Applicant: **Spot Zero Reverse Osmosis Inc.**, Fort Lauderdale, FL (US)

(72) Inventors: **Benjamin J. Koppenhoefer**, Fort Lauderdale, FL (US); **Jeffrey Alan Johnson**, Pahokee, FL (US); **Jake Zale Dudas**, Fort Lauderdale, FL (US); **Chad Edward Sullivan Tucker**, Oakland Park, FL (US)

(**) Term: **15 Years**

(21) Appl. No.: **29/968,886**

(22) Filed: **Oct. 18, 2024**

(51) **LOC (15) Cl.** **23-01**

(52) **U.S. Cl.**

USPC **D23/209**

(58) **Field of Classification Search**

USPC D23/200, 207, 209, 210, 231, 245, 246, D23/355, 362, 363, 365, 366; D24/162; D15/7, 9.1; D34/12

(57) **CLAIM**

The ornamental design for a portable reverse osmosis system, as shown and described.

DESCRIPTION

FIG. 1 is a first perspective view of a portable reverse osmosis system;

FIG. 2 is a front side view thereof;

FIG. 3 is a back side view thereof;

FIG. 4 is a right side view thereof;

FIG. 5 is a left side view thereof;

FIG. 6 is a top view thereof;

FIG. 7 is a bottom side view thereof; and,

FIG. 8 is a bottom perspective view thereof.

The subject matter in FIGS. 1 through 8 shown in broken lines illustrates wheels which form no part of the claimed design.

1 Claim, 8 Drawing Sheets
